UNITED STATES PATENT OFFICE

130,244

DESIGN FOR A PUMP

John H. Gerhardt, Beatrice, Nebr., assignor to
Dempster Mill Manufacturing Company, a cor-
poration of Nebraska

Application August 16, 1939, Serial No. 86,727

Term of patent 7 years

To all whom it may concern:

Be it known that I, John H. Gerhardt, a citizen of the United States, residing at Beatrice, in the county of Gage and State of Nebraska, have invented a new, original, and ornamental Design for a Pump, of which the following is a specification, reference being had to the accompanying drawings, forming part thereof.

Figure 1 is a perspective view of a pump showing my new design.

Figure 2 is a front elevational view thereof, and

Figure 3 is a rear elevational view.

The characteristic feature of the design resides in the pump disclosed having an enlarged upper portion and spout of the specific configurations shown.

I claim:

The ornamental design for a pump, as shown and described.

JOHN H. GERHARDT.
